INHALER AND METHOD OF
CONSTRUCTING IT

John William Arpin, Verona, N. J., assignor to
Tops Plastics, Inc., Orange, N. J., a corporation
of New Jersey

Application September 20, 1950, Serial No. 185,890

9 Claims. (Cl. 128—200)

1

This invention relates to inhalers and more particularly to a container which houses an inhalant substance.

The invention is particularly directed to most inhalers which contain an aromatic, fragrant element for freshening the breath. However, it may also be used for nasal inhalers as will be hereinafter made clear.

Inhalers having a breath sweetening element enclosed therein have been known for some time. An example thereof is one commercially designated as "Breath-O-Lator" which comprises a metal casing enclosing the aromatic element. Such element may take the form of a fibre member impregnated with the aromatic substance. Such substance may have a peppermint base or it could otherwise be agreeably perfumed.

It is an object of this invention to produce an inhaler of extremely simple construction so that it may be thrown away after the aromatic element has exhausted its usefulness. This is in contrast to many types of inhalers wherein they generally entail refilling. The inhaler of the instant invention is so cheap as regards cost of materials and production that it serves no purpose to save it after the element has dissipated its fragrance. In fact, it is hardly capable of refilling as will hereinafter be made clear. Notwithstanding the simplicity of the instant device, it nevertheless is completely effective for its intended purpose and in many respects is more desirable than more expensive devices.

The invention will be further understood from the following description and drawings in which:

Fig. 1 is a separated view of the container and aromatic element normally contained therein.

Fig. 2 is a front elevational view of the composite article.

Fig. 3 is a side view thereof.

Fig. 4 is an enlarged cross-sectional view as taken along the lines 4—4 of Fig. 2.

Fig. 5 is a cross-sectional view as taken along the lines 5—5 of Fig. 4.

Fig. 6 is a cross-sectional view as taken along the lines 6—6 of Fig. 4.

Fig. 7 is a front elevational view of a modified embodiment.

Fig. 8 is an enlarged cross-sectional view as taken along the lines 8—8 of Fig. 7.

Fig. 9 is a cross-sectional view as taken along the lines 9—9 of Fig. 8.

The main embodiment is illustrated in Figs. 1 to 6. It comprises a tube 10 and an aromatic element 11 which is enclosed therein. It will be recognized that the aromatic element 11 may

2

take any suitable and conventional form. The tube 10 is preferably but not necessarily formed of a resilient plastic material although it may be formed of a metal. However, it exhibits particularly marked advantages when formed from a resilient plastic such as polyethylene or polythene. This material is resilient when formed in thin sheets or walls and has a soft feel which is agreeable to the mouth or lips of the user. 10 The article is assembled by disposing the aromatic element 11 within the tube 10 and sealing the ends of the tube to permanently enclose the element 11 therein. Pursuant to the instant invention, the seal is such as to automatically leave air openings through which the aroma or fragrance of element 11 may be inhaled.

Referring to Fig. 2, after the element 11 has been enclosed within the tube 10, the ends of the tube are centrally pinched at points 12 and 20 13 and sealed thereat. These seals are in the nature of a spot-weld as illustrated in Figs. 4 and 5. Such sealing pinches the ends of the tube 10 and automatically produces end openings 14. Thus, it will be seen in Fig. 5 that the weld 25 or seal 13 produces the two openings 14 on either side thereof which permits the fragrance of the aromatic element to be inhaled but which seals it in the tube and protects it against loss. Polyethylene is an excellent substance for this purpose because it is rather inert and satisfactorily encloses the vapors against dissemination other than through the openings 14.

As illustrated in Figure 6, the resilient tube 10 is substantially cylindrical or round in cross-section although the pinch seals 12 and 13 keep the ends in a sealed state against a tendency of such ends to return to a normally cylindrical shape. The resiliency of the tube thus produces the corner openings 14 on both sides of the seal.

It will be recognized from the foregoing that the inhaler above described is of remarkably cheap yet efficient construction. It is only necessary to insert the aromatic or vaporizable element into the tube 10 and pinch-seal the ends automatically providing openings 14 for vaporous inhalation. The resiliency of the plastic and the normally open ends of the tube contribute to the formation of such openings when the ends are pinched. However, even if the tube 10 is of rigid material such as aluminum, the openings will also be formed as above described. The article, when made of polyethylene, is easy and pleasant to use since it is very light and does not have the cold feel of metal. It is desirable 45 to have the openings 14 at both ends of the tube

or container so as to have a uniform and reliable air flow.

The seal may be effected by a heat, spot-welding process since the tube material is thermoplastic. Of course, a solvent could be used in connection therewith.

Inasmuch as the air openings 14 are exposed, the article may be enclosed, if desired, in a sealed cellophane bag or the like until ready for use. On the other hand, it is quite simple to employ a cap over the ends of the tube if desired.

In the embodiment of Figs. 7 to 9, the body or container 15 comprises a sheet of polyethylene which is folded and sealed along the longitudinal edge 16 to produce a substantially tubular body. It is also sealed at the end edges 17 and 18. Thereafter, the corners 19 are cut away to produce the vapor or air openings. The corners may be weakened or scored along the lines 20 so that the user may remove the corners. However, it is more advantageous to remove the corners when the article is produced and to enclose it in an air impermeable bag and until ready for use by the consumer.

The article may also be used as a nasal inhaler as will be evident.

What is claimed is:

1. An inhaler comprising an elongated tubular body containing a vaporizable element, said tubular body being centrally pinched and sealed at both ends thereof and having corner openings formed at either side of the pinch.

2. An inhaler comprising a tubular body of resilient plastic material, said tubular body being centrally pinched and sealed at both ends thereof and having corner openings formed at either side of the pinch, the end seals maintaining the central pinches against the normal tendency of said body to open thereat.

3. An inhaler according to claim 2 and wherein said body is fabricated of polyethylene.

4. An inhaler comprising an elongated tubular body of resilient plastic material and containing a vaporizable element, said body being normally open-ended and being centrally pinched and sealed at its ends, said ends having air openings formed on both sides of the pinched seal, and said seal maintaining said body end centrally pinched against a tendency to return to its normally open-ended state.

5. An inhaler comprising an elongated tubular body of resilient plastic material and containing a vaporizable element therein, said body being pinch sealed at the center of each end thereof

and having corner openings formed on both sides of the seal at each end.

6. A method of housing an inhalant member in a resilient thermoplastic, open-ended tubular body which comprises inserting the member therein and heat sealing a portion of the open ends of the tubular body so as to contain the member therein while leaving end openings for the passage of air.

7. A method of housing an inhalant member in a thermoplastic, normally open-ended tubular body which comprises inserting the member therein and thereafter heat sealing a central spot of both normally open ends of the body whereby corner edge openings at both sides of the seals are formed.

8. An inhaler comprising a normally substantially cylindrical tubular body of resilient plastic material containing a vaporizable element, said tubular body being centrally sealed at at least one end thereof against a normal tendency to return to substantially cylindrical at said point of seal, and said one end having at least one opening formed adjacent to the seal.

9. An inhaler comprising a normally substantially cylindrical tubular body of resilient, plastic material containing a vaporizable element, said tubular body being centrally sealed at both ends thereof and having a corner opening formed at either side of the pinch at each end, the seals maintaining the two corner openings at each end against the normal tendency of the resilient tube to return to substantially cylindrical shape at the ends.
